EDUCATIONAL GAME BOARD OR SIMILAR ARTICLE

James T. Kenney and Charles J. O'Loughlin, Silver Spring, Md., assignor of 33½ percent to John E. Becker, Takoma Park, Md.

Continuation of design applications Ser. No. 62,156 and 62,157, Sept. 15, 1960. This application Mar. 13, 1962, Ser. No. 69,240

Term of patent 14 years

(Cl. D34—5)

FIG. 1.

FIG. 2.

FIG. 3.

FIG. 4.

FIG. 5.

FIG. 1 is a top plan view of an educational game board, showing one form of our new design, wherein the outer pathway is rectangular and is disposed along the four marginal sides of the playing board, and wherein said board is provided with four circular work areas disposed within the four quadrants formed by a cruciform shaped set of home pathways;

FIG. 2 is a cross-sectional view as taken on line 2—2 of FIG. 1;

FIG. 3 is a top plan view of an educational game board, showing a modified form of our new design, wherein the rectangular shaped pathway is disposed in a generally diamond form with the corners thereof bisecting the four sides of the playing board, and having the four circular work areas disposed in the outer four corners of the playing board, outwardly adjacent the respective four sides of the rectangular pathway;

FIG. 4 is an edge elevational view of the board of FIG. 3; and

FIG. 5 is a cross-sectional view as taken on line 5—5 of FIG. 3.

The dominant features of our design reside in those portions shown in full lines.

This application is a continuation of our prior co-pending design applications, Serial Numbers D. 62,156 and D. 62,157, filed September 15, 1960, and now abandoned.

We claim:

The ornamental design for an educational game board or similar article, substantially as herein shown and described.
